SWAGE SHAPER

Otis E. Moore, P.O. Box 451, Quincy, Calif.

Filed Oct. 14, 1958, Ser. No. 767,163

12 Claims. (Cl. 76—51)

This invention relates to swage shapers and more particularly to a swage shaper for shaping the cutting teeth of a band saw.

An object of the invention is to provide an air powered band saw tooth swage shaper provided with a novel pneumatically operated drive train between the piston rod of a double acting pneumatic cylinder and the die holders of the shaper.

Commercially available swage shapers use screw feed arrangements for the die holders. When the screw feed wears out the main casting or head must be discarded. This is an expensive repair. With a cam or eccentric drive as described in this invention, the head need never be discarded unless it is broken. If any parts wear in the swage shaper of this invention, they will only be small, easily and cheaply replaced parts.

The pneumatic shaper of this invention provides a more uniform shaped tooth than does a hand powered shaper, since human fatigue does not enter as a consideration. Furthermore, an air powered shaper may be made smaller and lighter than any shaper on the market because of the comparatively short distance the air cylinder piston must travel in order to actuate the die holders through the full stroke thereof.

A more particular object of the invention is to provide a swage shaper which has mounted on a convenient frame, a double acting pneumatic cylinder which is connected by an adjustable cross head to the outer ends of a pair of eccentric shaft operating levers. The eccentric shafts are identical, each having an eccentric and collar to which a push rod is fixed. The push rods project inwardly of each other and have specially contoured ends to engage with bearing surfaces on die holders that are pivoted to the frame. The die holders are spaced apart so that when the dies are in place, there remains a throat within which to accommodate the teeth of a band saw.

When the piston in the double acting cylinder is reciprocated by operation of a valve to admit air on alternate sides of the piston in the cylinder, the two levers are simultaneously oscillated and this will cause the eccentric shafts to which they are secured to be correspondingly oscillated. Assuming a 90° oscillation, the eccentric collars are moved to a predetermined distance and this moves the push rods the same distance so that the die holders are moved accordingly. Swaging and shaping takes place in this way.

There are a number of features in the swage shaper making it easy to adjust and handle. For instance, there is an adjustable stop for the teeth in order to assure that the swaging operation will take place at the same location on each successive tooth of a band saw. Since the pneumatic cylinder-lever and cross head arrangement is used, only a short stroke is necessary thereby minimizing the length of the cylinder and consequently, the over-all length dimension of the swage shaper.

These together with other objects and advantages which will become subsequently apparent reside in the details of construction and operation as more fully hereinafter

2

described and claimed, reference being had to the accompanying drawings forming a part hereof, wherein like numerals refer to like parts throughout, and in which:

Figure 1 is a top view of the swage shaper.

Figure 2 is a side view of the swage shaper in Figure 1.

Figure 3 is a sectional view taken on the line 3—3 of Figure 1.

Figure 4 is a longitudinal sectional view taken on the line 4—4 of Figure 1.

Figure 5 is a bottom plan view of the swage shaper.

Figure 6 is a fragmentary bottom plan view of the shaper, showing it in a second position with reference to the position in Figure 5.

Figure 7 is a sectional view taken on the line 7—7 of Figure 1.

Figure 8 is a sectional view taken on the line 8—8 of Figure 2.

Figure 9 is a sectional view taken on the line 9—9 of Figure 3.

Figure 10 is a sectional view of the valve taken on the line 10—10 of Figure 2.

Figure 11 is a perspective view of one of the die holders and dies of the swage shaper.

In the accompanying drawings there is a swage shaper 10 constructed to exemplify the principles of the invention. The swage shaper has a frame 12 functioning as the structural support for the various parts of the shaper. Although the frame may assume a number of different configurations, it is preferred that the frame be made of a substantial casting having a plate 14 with a pair of coplanar forks 16 and 18 near one end. Each pair 16 and 18 of forks is made of two sides slightly spaced from each other, there being sides 20 and 21 together with sides 22 and 23 (Figure 7). Guard 24 consisting of parallel plates 26 and 28, depends from plate 14 with the guard plates straddling saw 30 when the shaper is in use.

A double acting pneumatic cylinder 32 is attached to plate 14 of frame 12, for instance by bolts 34, and is attached to the frame 12 at its opposite end, for instance by screw 36 in a small bracket 40 of frame 12. The double acting pneumatic cylinder is conventional to the extent that it has an ordinary piston 42 to which piston rod 44 is attached. The stroke of the piston is established by contacting the boss 46 on cylinder head 48 and by contacting the inner end of screw 50 that is adjustably carried by head 52 of the cylinder. The stroke of piston 42 is altered by adjusting screw 50, whose outer end has a hand knob 54 or like handle thereon.

Piston rod 44 is made to reciprocate by the application of air under pressure to alternate sides of piston 42. To do this manually operated valve 56 is attached to bracket 58 of frame 12. The bracket may be made as an integral part of the casting of frame 12 or may be attached to a reinforcing rib 60 extending between the pairs 16 and 18 of forks. The valve 56 is made of a solid valve core 62 movably mounted in valve casing 64. Core 62 has two air feed passages 66 and 68 completely through it and at right angles to each other and at opposite ends of the core. Two exhaust channels 70 and 72 are in the surface of the core so that when air is fed through one passage, air from the other end of the cylinder will exhaust through the other feed passage of a common exhaust port 74 in valve casing 64. A stop groove 76 is in one end of the valve core and there is a stop pin, for instance bolt 78, carried by the valve casing and disposed in the stop groove 76 so that the valve core may move only through a 90° travel. Handle rod 80 is secured to the valve core and has a handle 81 thereon to adjust the setting of valve 56.

Air intake manifold 82 is attached to the valve casing 64 and registers with the two air inlet ports 84 and 86 in casing 64, with the inlet ports adapted to register with

the right angularly disposed passages 66 and 68 depending on the setting of the valve core. The valve outlet ports 89 and 90 have air conductors 91 and 92 attached to them, and these extend to the ports 93 and 94 (Figure 4) of the double acting pneumatic cylinder 32 so as to apply air under pressure alternately to the faces of piston 42 and thereby cause the piston rod 44 to be reciprocated through packing gland 95 in cylinder head 48.

There are two die holders and two dies in the swage shaper. Die holders 100 and 102 are identical and the same holds true of dies 104. Typical die holder (Figure 11) is made of a bar having a bore 106 near one end and a half-round surface 108 near the opposite end. Slot 110 extends through the die holder in order to receive the die retention bolt 112 and washer 114. Die 104 is conventional in its function and configuration, and is held to the die holder 100 by retention bolt 112. Pin 116 is secured to holder 100 and it enters a small slot in a part of frame 12 (Figure 9) and fits between a pair of springs or adjacent coils of a single spring 118 that is captive in bore 120 that registers with the small slot through which pin 116 is passed. Spring 118 functions as a return spring for the die holder 100 when the die holder and die is being oscillated in its shaping function.

As shown in Figure 7 the die holders and dies are spaced slightly from each other to form a throat 126 within which to accommodate the teeth of blade 30. The throat is in axial alignment with the space between plates 26 and 28. In addition there is a tooth stop 128 located in throat 126 and adapted to abut the teeth of the saw so that each tooth is swage shaped with uniformity. Tooth stop 128 has an upper part 130 (Figure 2) that is held to the top surface of frame plate 14 by a bolt 132 passing through a slot whereby the location of the stop 128 in throat 126 may be altered. However, once adjusted it remains in place until the particular blade being shaped has been completed.

Reference is now made to Figure 9 to observe how the die holders are mounted. One end of typical holder 100 has a pivot 138 extending through bore 106 and attached to a part of the frame 12. The opposite end of the holder 100 is disposed on the surface of a supporting bracket 139 which is secured to frame 12. Therefore holder 100 is capable of being oscillated back and forth with the longitudinal axis of pin 38 establishing the axis of oscillation of holder 100. These movements, though, are yieldingly opposed by spring 118. An important feature of the invention is found in the means for so oscillating the die holders. These means consist of a pair of curved levers 142 and 144 whose adjacent ends are attached to adjustable cross head 146 and whose outer ends have split clamps 148 and 150 secured to collars 152 and 154 on eccentric shafts 156 and 158. The eccentric shafts have eccentrics 160 and 162 between their ends, and bearings 164 and 166 on opposite sides of eccentric 160; and bearings 168 and 170 on opposite sides of eccentric 162. Bearings 164 and 166 are held in aligned openings in the two sides 22 and 23 of fork 18, and bearings 168 and 170 are held in aligned openings in sides 21 and 20 of fork 16. The collars 152 and 154 may be held in place on the extending upper ends of shafts 156 and 158 by any suitable means, for instance by setscrews or by having the collars and shafts made with square openings and cross-sections respectively. In any case, the levers 144 and 142 cause the eccentric shafts to be oscillated in response to reciprocation of piston rod 44. Cross head 146 is made of a split sleeve 178 threaded to a selected place on piston rod 44 and clamped in place by a bolt. A pair of links 180 and 182 are pivoted to the cross head 178 and to the inner 70 adjacent ends of the levers 144 and 142 thereby establishing a drive connection between the piston rod 44 and the levers 142 and 144.

Collars 188 and 190 for the eccentrics 160 and 162 are disposed on bearings 192 and 194 located on these 75

eccentrics 160 and 162. Two push rods 196 and 198 are welded or otherwise fastened to collars 188 and 190, and they extend through passages 200 and 202 in the confronting sides of forks 16 and 18. The confronting 5 ends of the push rods 196 and 198 are contoured hollow to engage the half-round surfaces 108 of the die holders 100 and 102. It is now evident that oscillation of eccentric shafts 156 and 158 by levers 142 and 144 will cause the push rods 196 and 198 to oscillate the die holders 100 and 102. This accomplishes the saw tooth swage shaping operation.

Adjustable stop 128 is contacted by an edge of the saw teeth and this establishes the correct position of the shaper along the length of the saw. The correct position 15 of the saw and shaper with reference to a transverse axis is established by bolts 240 and 242 which are attached to the front part of the guide plates 28 and 26. These bolts are adjustable and are used for contacting the sides of the saw. With this swage shaper tooth shaping 20 may be accomplished easier, with greater accuracy and much more rapidly than any other known shaper. Further, it is explicitly pointed out that the pneumatic cylinder is a short stroke cylinder which, through the action of the pair of levers and eccentrics on eccentric 25 shafts, furnishes adequate operational motion and power for the die holders. The shortness of stroke is an important factor because the swage shaper is manually handled and therefore, with a short stroke, the length of the cylinder and piston may be made short thereby reducing 30 the bulk of the shaper.

The foregoing is considered as illustrative only of the principles of the invention. Further, since numerous modifications and changes will readily occur to those skilled in the art, it is not desired to limit the invention to the 35 exact construction and operation shown and described, and accordingly, all suitable modifications and equivalents may be resorted to, falling within the scope of the invention as claimed.

What is claimed as new is as follows:

1. A tooth swage shaper for shaping the cutting teeth of a saw, said shaper comprising a frame, a cylinder attached to said frame and having a piston rod, a pair of shafts mounted in said frame and having eccentrics, collars on said eccentrics, push rods fixed to said collars, spaced die holders pivoted to said frame and contacted by said push rods so that said holders are moved toward each other in response to rotation of said eccentric shafts to swage a saw tooth located in the space between said die holders, and means drivingly connecting said piston rod to said levers for oscillating said levers as said piston rod is reciprocated.

2. A tooth swage shaper for shaping the cutting teeth of a saw, said shaper comprising a frame, a cylinder attached to said frame and having a piston rod, a pair of shafts mounted in said frame and having eccentrics, collars on said eccentrics, push rods fixed to said collars, spaced die holders pivoted to said frame and contacted by said push rods so that said holders are moved toward each other in response to rotation of said eccentric shafts 55 to swage a saw tooth located in the space between said die holders, means drivingly connecting said piston rod to said levers for oscillating said levers as said piston rod is reciprocated, said pneumatic cylinder being double acting, and a valve having air conductors connected with said cylinder to apply pressure to said cylinder and reciprocate said piston rod.

3. The tooth swage shaper of claim 2 wherein said die holders are each pivoted at one end and have bearing surfaces near their opposite ends, and said push rods having ends in contact with said bearing surfaces.

4. In a tooth swage shaper for a band saw, the combination of a frame having a pair of spaced forks whose sides have aligned openings, an eccentric shaft mounted in the openings in each of said forks, an eccentric driven push rod and collar operatively connected with each ec-

centric shaft, a pair of levers connected to each shaft, a double acting pneumatic cylinder secured to said frame and having a piston rod, means coupling said levers to said piston rod for oscillating said levers and thereby oscillating said eccentric shafts and push rods, a pair of die holders mounted on said frame and having a throat forming space therebetween to receive the teeth of the saw, dies carried by said die holders, and said push rods contacting said die holders to move said dies into said throat and toward each other in response to actuation of said levers.

5. In a tooth swage shaper for a saw, the combination of a frame having a pair of spaced forks whose sides have aligned openings, an eccentric shaft mounted in the openings in each of said forks, an eccentric driven push rod and collar operatively connected with each eccentric shaft, a pair of levers connected to each shaft, a double acting pneumatic cylinder secured to said frame and having a piston rod, means coupling said levers to said piston rod for oscillating said levers and thereby oscillating said eccentric shafts and push rods, a pair of die holders mounted on said frame and having a throat forming space therebetween to receive the teeth of the saw, dies carried by said die holders, said push rods contacting said die holders to move said dies into said throat and toward each other in response to actuation of said levers, and a tooth stop adjustably secured to said frame and located in said throat to contact the saw teeth and establish a similar shaping position for each tooth of the saw blade.

6. In a tooth swage shaper for a saw, the combination of a frame having a pair of spaced forks whose sides have aligned openings, an eccentric shaft mounted in the openings in each of said forks, an eccentric driven push rod and collar operatively connected with each eccentric shaft, a pair of levers connected to said shaft, a double acting pneumatic cylinder secured to said frame and having a piston rod, means coupling said levers to said piston rod for oscillating said levers and thereby oscillating said eccentric shafts and push rods, a pair of die holders mounted on said frame and having a throat forming space therebetween to receive the teeth of the saw, dies carried by said die holders, said push rods contacting said die holders to move said dies into said throat and toward each other in response to actuation of said levers, and at least one of said stops being adjustable and thereby providing means to alter the stroke of the piston.

7. In a swage shaper for a saw, the combination of a frame, a pair of die holders, means at one end of each die holder pivotally mounting the die holder on said frame, said die holders having a saw tooth throat therebetween, a cylinder having a piston and secured to said frame, a pair of levers, means including a cross head on the piston rod of said cylinder for oscillating said levers in unison, means carried by said frame and connected with said levers for moving said die holders inwardly of said throat and toward each other in response to reciprocation of said piston rod, and yielding means reacting on said frame for opposing the movement of said die holders.

8. In a swage shaper for a saw, the combination of a frame, a pair of die holders, means at one end of each die holder pivotally mounting the die holder on said frame, said die holders having a saw tooth throat therebetween, a cylinder having a piston and secured to said frame, a pair of levers, means connected to said piston rod for oscillating said levers in unison, means carried by said frame and connected with said levers for moving

said die holders inwardly of said throat and toward each other in response to reciprocation of said piston rod, and yielding means opposing the movement of said die holders, said die holders moving means including a parallel pair of shafts having eccentric collars on said eccentric, and push rods fixed to said collars and extending toward said throat, means engaging the inner ends of said push rods with said die holders.

9. In a swage shaper for a saw, the combination of a frame, a pair of die holders, means at one end of each die holder pivotally mounting the die holder on said frame, said die holders having a saw tooth throat therebetween, a cylinder having a piston and secured to said frame, a pair of levers, means connected to said piston rod for oscillating said levers in unison, means carried by said frame and connected with said levers for moving said die holders inwardly of said throat and toward each other in response to reciprocation of said piston rod, yielding means opposing the movement of said die holders, said die holders moving means including a parallel pair of shafts having eccentric collars on said eccentric, push rods fixed to said collars and extending toward said throat, means engaging the inner ends of said push rods with said die holders and including raised surfaces on said die holders, and contoured surfaces at the inner ends of said push rods and in engagement with said raised surfaces of said die holders.

10. In a swage shaper for a saw, the combination of a frame, a pair of die holders, means at one end of each die holder pivotally mounting the die holder on said frame, said die holders having a saw tooth throat therebetween, a cylinder having a piston and secured to said frame, a pair of levers, means including a cross head on the piston rod of said cylinder for oscillating said levers in unison, means carried by said frame and connected with said levers for moving said die holders inwardly of said throat and toward each other in response to reciprocation of said piston rod, yielding means reacting on said frame for opposing the movement of said die holders, a tooth stop projecting into said throat, and means adjustably securing said tooth stop to said frame.

11. In a swage shaper for a saw, the combination of a frame, a pair of die holders, means at one end of each die holder pivotally mounting the die holder on said frame, said die holders having a saw tooth throat therebetween, a cylinder having a piston and secured to said frame, a pair of levers, means including a cross head on the piston rod of said cylinder for oscillating said levers in unison, means carried by said frame and connected with said levers for moving said die holders inwardly of said throat and toward each other in response to reciprocation of said piston rod, yielding means reacting on said frame for opposing the movement of said die holders, adjustable means carried by said frame and on opposite sides of said throat for contacting the sides of the saw to center the swage shaper on the saw, and an adjustable tooth stop carried by said frame and having a part projecting into said throat.

12. The swage shaper of claim 7 wherein said double acting cylinder is pneumatically operated, and a valve carried by said frame and operatively connected with said pneumatic cylinder to actuate the piston thereof.
